US0D1059015S

(12) United States Design Patent (10) Patent No.: US D1,059,015 S
(45) Date of Patent:  Jan. 28, 2025

(54) SHOE

(71) Applicant: Birkenstock IP GmbH, Linz am Rhein (DE)

(72) Inventor: Ronnie Fieg, New York, NY (US)

() Term: 15 Years

(21) Appl. No.: 35/518,624

(22) Filed: Sep. 14, 2023

(80) Hague Agreement Data

Int. Filing Date: Sep. 14, 2023

Int. Reg. No.: DM/231939

Int. Reg. Date: Sep. 14, 2023

Int. Reg. Pub. Date: Oct. 13, 2023

(30) Foreign Application Priority Data

May 2, 2023 (EM) 015020350-0002
May 2, 2023 (EM) 015020350-0004

(51) LOC (15) Cl. 02-04

(52) U.S. Cl.

USPC D2/969; D2/923; D2/924

(58) Field of Classification Search

USPC D2/902-912, 916-926, 969-978
